T. Potter, Sr.

Balance Scales.

Patented Dec. 17, 1834.

Dec 17. 1834

Thomas. Potter, Senr. of the County of Warren, Kentucky.

Letters Patent.

8543*

The schedule referred to in these Letters Patent and making part of the same containing a description in the words of the said Thomas Potter Senr himself of his improvement in a machine for removing weight from place to place & for loading and unloading Boats warehouses &c.

To all to whom these presents shall come;

Be it known that I Thomas Potter Senr. of the County of Warren and State of Kentucky, have invented a new and useful improvement in Mechanics to wit. A machine or engine for removing weight from place to place & for loading & unloading Boats Warehouses &c &c and that the following is a full and exact description of the construction and operation of the said machine or engine as invented or improved by me,

Beams of strong timber or other material, 55 feet in length, more or less, and a foot square more or less, are to be procured, if 55 or more feet in length is desired, the timber may be split so as to consist of more than a single beam. These beams are to be elevated to any height desired, and are to be supported by strong posts, standing perpendicular or otherwise, and sufficiently numerous to prevent the beams from swagging and the rows of posts at bottom, to be 8 feet apart, more or less, the two beams are to be precisely horizontal & parallel with each other, and may be placed at any desirable distance apart, say one foot more or less. The ends of these beams, are to be connected together by strong timber or other material, so as to cause the beams to obtain their parallel position.

From the upper outside of these beams, there is to be raised perpendicular side rails composed of timber or other suitable material, three inches thick, more or less, these side rails are to be connected at their ends by rails of equal height.

On the upper sides of these beams, are to be laid iron or steel rails or plates, to extend from one end to the other, two inches in breadth, more or less. A car is to be constructed of 4 wheels 10 inches, more or less, in diameter of cast iron or other suitable materials and with or without flanges, and the wheels of the one to be

Drawing See class of Patents

suitable widths to run on the rails or plates aforesaid. If the wheels are made without flanges, then the car is to be kept to its proper place and made to run on the rails or plates by means of horizontal friction wheels placed in the car, so that their peripheries will just bear against the side rails which must be of such height as will allow the friction wheels of the car to come in contact with them. The axletrees of the cars are to be of iron or other suitable material 2 inches in diameter, more or less, and are to be let into a block 6 feet in length more or less and 2 $\frac{1}{2}$ feet wide, more or less, into which block mortises are made to let the wheels revolve freely around the axletrees according to the model herewith sent, thus the center of this block which constitutes the car, a hole is to be morticed 18 inches in length more or less, 4 $\frac{1}{2}$ wide more or less, on the top of the block suitable notches on each side of the mortises are to be cut, for the elevator to rest in. The elevator is an instrument made like a common jack, upon the bar of which is to be ten feet long, more or less, and is to pass down thro' the hole morticed in the center of the block, and into the opening left between the parallel beams. At the end of the bar there is to be a swivel to which a scale or grapple is attached, so that the scale may be turned around as convenience may dictate. The scale or grapple in view of the scale is to receive the weight intended to be moved, whatever it may be. It is then to be raised by turning the levers which work the elevating bar, and then carried to the place desired by moving the car on the rails. The weight to be moved is to swing below the car and rails instead of an elevator constructed upon the principle of the jack screw if found to be more convenient, a system of pulleys may be used by attaching them to the car, or in place of the pulleys, the wheel and axle or windlass may be used, and whether the one or the other is used the weight is to be elevated so as to swing under the car and rails and then to be moved to the place desired, by moving the car on the rails. The beams and rails therefore may not be horizontal and still they will, by means of the car to run on them as aforesaid, and the elevator be very useful in performing the same services which are contemplated to be performed when precisely horizontal when the beams make an angle with the horizon, the car may be made to ascend by means of a windlass attached to either end of the beams.

8543 X 191

a rope or chain connecting or attaching the car to the roadways I design using the foregoing machine or engine for the following purposes. First-in loading or unloading boats, ships, and water craft of every kind, the model to be used shows a projection of seven feet over each end of a boat from which it is apparent that a load of rock, or heavy material of any kind may be taken in at one end, put out at the other & placed conveniently in any part of the boat, such a boat and machine attached would be very useful in building Mill Dams removing rock on water courses &c &c

Second-in transporting heavy articles of merchandizing and produce from warehouses to wharves and from wharves to warehouses, this is to be done by constructing a stationary way by beams placed horizontally or at an angle with the horizon on posts let into the ground as already described.

Third, In transporting heavy burdens of all kinds and descriptions, by erecting permanent or temporary ways as aforesaid, and to be used in removing rock, earth, wood, logs, minerals, and every conceivable article from place to place. The machine for these purposes will be useful in removing rock, and dirt from cellars, supplying saw mills with raw logs, & for all other purposes where it is desirable to remove heavy weight with ease and convenience.

My invention chiefly consists in the construction of a way for transporting heavy weight in such manner as to allow the weight transported to swing below the way on which the car is to travel to which car the weight is to be attached as already described. The invention may be denominated the elevating and transporting rail way or engine.
